UNITED STATES PATENT OFFICE.

ANDRES F. WAHLBERG, OF EAST ORANGE, NEW JERSEY.

CALIPERS.

Application filed April 4, 1927. Serial No. 180,820.

This invention relates to combined calipers and dividers which may be employed for obtaining the inside and outside measurements with one adjustment. It is possible by means of this instrument to measure the inside dimensions of an opening and simultaneously if desired the outside measurement of the piston which is to fit within said opening.

Further detail features of the invention will be apparent from the following description and will be set forth in the appended claims.

In the drawings:

Figure 1 is a top plan view of the invention showing the same employed for measuring both inside and outside dimensions.

Figure 2 is a similar view with parts in section and the legs of the calipers in a different position.

Figure 3 is a longitudinal section on the line 3—3 of Figure 2.

Figure 4 is a transverse section on the line 4—4 of Figure 2.

The calipers constituting the subject matter of this invention comprise a pair of members 1 and 2 which are identical in form and which are pivoted together to turn about an axis 3. This pivot comprises a screw headed bolt 4 which passes through both members and through a hollow housing 5 and may be riveted as at 6 on the outside of this housing. Other fastening means may be employed if desired.

Coiled about the bolt 4 and within the housing is a spring 7 which has one arm 8 extending through an opening in the housing and bearing against the leg 2 of the calipers while the other end of the spring 9 extends through a similar opening and bears against the leg 1 of the calipers. This spring tends to force the calipers about the pivotal axis 3 in the direction indicated by the arrows in Figure 2.

Posts 10 and 11 are pivotally carried by the legs 2 and 1 respectively at one side of the pivotal point and are held in position by screws 12 and 13 respectively or by other similar fastening means. Each of these posts is provided with a transverse opening therethrough in which fits a screw threaded rod 14. On this rod is provided a threaded nut 15 between which and one of the posts is interposed a bushing or washer 16. The posts may be provided with thumb screws 17 and 18 respectively as shown in Figure 4

which may be screwed down upon the rod 14 to lock the parts in adjusted position. If desired, however, the end of the rod which engages in the posts 10 may be riveted or otherwise fastened in position and in this case the thumb screws 17 and 18 may be omitted.

One end of each member of the calipers terminates in a sharp point 19 enabling the same to be employed as dividers. At a point 65 slightly removed from the end each leg of the calipers has on the outside thereof a projection 20 terminating in a sharp point. The other end of each leg of the calipers is curved inward in the usual manner and terminates in a point 21.

The spring 7 acts to move the calipers toward an open position in which the washer 16 engages against the post 11. Whenever it is desired to adjust the calipers it is only 70 necessary to turn the thumb screw 15 whereupon the calipers will be moved positively toward a closed position or will be allowed to expand to a more open position under the influence of the spring 7. The points 20 75 serve for measuring the inside dimensions of a cylindrical object such as indicated at X, while the points 21 serve for the purpose of measuring the outside dimensions of a piston or similar object Y.

One of the important features of the invention resides in the fact that the distance from the axis 3 about which the members of the calipers move to the points 20 is exactly the same as the distance to the points 21. When the calipers are adjusted so that the points 20 give the desired inside dimension, then the points 21 will measure exactly the same outside dimension. This operation is clearly indicated in Figure 1 of the drawings. Accordingly there is no necessity for reading the particular adjustment of the inside dimensions on a scale and then setting the calipers again for the purpose of reading the outside dimensions. All likelihood of error in the various adjustments is 80 eliminated and it is possible to measure both inside and outside dimensions simultaneously or in sequence without error.

It is obvious that various details of the 85 precise construction may be modified widely without in any way departing from the spirit of the invention, which is to be regarded as limited only by the scope of the appended claims.

I claim as my invention:

1. Calipers comprising two similar members pivoted to turn about an axis, one end of each of said members being pointed to form dividers and having an outer projection near said end adapted to measure inner dimensions, the other end of each member being turned inwardly to permit measuring of outer dimensions, the inner and outer dimensions measured being the same for each 10 adjustment of the members.

2. Calipers comprising two similar members, a pivot holding said members together, a post fastened to each member, one of said

posts having an opening therethrough, a screw-threaded rod fastened to the other post and passing through said opening, a screw threaded member on said rod and adapted by its adjustment to move one member relatively to the other in one direction and a spring having its central portion coiled about said pivot and its ends engaging said posts for normally tending to move the similar members in the opposite direction.

In testimony whereof, I have hereunto subscribed my name.

ANDRES F. WAHLBERG.
